United States Patent Office

Des. 181,560
Patented Nov. 26, 1957

181,560

STEP

Randolph R. Varnado, Sr., Port Arthur, Tex.
Application March 18, 1954, Serial No. 29,599

Term of patent 14 years
(Cl. D13—7)

Figure 1 is an isometric view of a step embodying my new design, and

Figure 2 is a transverse sectional view of the step.

I claim:

The ornamental design for a step, as shown.

References Cited in the file of this patent

UNITED STATES PATENTS

1,963,866	Peterson	June 19, 1934
2,289,439	Kogl	July 14, 1942